MEANS FOR PREVENTING THE STRETCHING OF FLEXIBLE
ARMOR FOR ELECTRIC CONDUCTORS

Filed April 6, 1928

Inventor

Frederick W. Kulicke

Attorney

UNITED STATES PATENT OFFICE

FREDERICK W. KULICKE, OF PHILADELPHIA, PENNSYLVANIA, ASSIGNOR, BY MESNE ASSIGNMENTS, TO THE ELECTROLOCK MANUFACTURING COMPANY, OF VICKSBURG, MISSISSIPPI, A CORPORATION OF MISSISSIPPI

MEANS FOR PREVENTING THE STRETCHING OF FLEXIBLE ARMOR FOR ELECTRIC CONDUCTORS

Application filed April 8, 1928. Serial No. 268,048.

In ignition systems, particularly the ignition systems for automobiles and the like, it is quite common to protect certain of the electric conducting means by means of flexible armor. For example, the flexible conductor between the lock switch means which may be mounted upon the dash-board of an automobile and the timer distributor may be protected by means of a flexible coil constituting an armor therefor. I have chosen to illustrate my invention as applied to a flexible armor employed for the protection of a conductor extending between the switch casing and a timer distributor.

It has been found that without the presence of means to prevent the stretching of flexible cables workmen are apt to and frequently do take hold of the flexible coil and inadvertently or for some other reason exert a pull thereon which results in a stretching action thereof, after which not infrequently it is found that the conductor either has been broken or otherwise disconnected.

The general object of the present invention is to provide means in association with a flexible coil and the conductor armored thereby whereby pulling upon the coil will not result in the stretching thereof and breakage or disruption of the conductor inclosed thereby is prevented.

It also is an object of the invention to provide within a coil of wire, constituting a flexible armor for an electric conductor, a flexible wire connected at its opposite ends to the coil and anchored with the coil at its opposite ends in supporting non-yielding means, whereby the coil is prevented from stretching upon the application of a pulling or stretching force thereon.

To these and other ends the invention comprehends the construction and arrangement as hereinafter described in detail, particularly pointed out in the claims, and as illustrated in the accompanying drawings in which I have shown one form of embodiment of the invention. However, it is to be understood that the invention is not limited to the details of construction as illustrated and that changes in the construction may be made within the scope of the claims without de-

parting from the invention or the principle thereof.

In the drawings:

Fig. 1 is a view showing in longitudinal section a flexible wire coil constituting an armor for a conductor, the said conductor and the means for preventing stretching of the said coil being shown in elevation and the opposite ends of the coil and of the said means having rigid permanent connection with a switch lock casing and with a timer distributor; and

Fig. 2 is a transverse sectional view taken on the line 2—2 of Fig. 1.

In the drawings I have shown at 1 the casing of a switch by means of which the circuit of the ignition system may be controlled in any known manner. A flexible electric conductor 2 is connected at one end to the said casing as indicated at 3 and at its opposite end to a timer distributor 4 as indicated at 5. The conductor is protected by means of a flexible armor 6 consisting of a coiled wire as shown, which armor extends practically from end to end of the conductor 2 and is secured at its opposite ends in sleeves or thimbles 8 and 9, the former being secured permanently to the casing 1 and the latter to the casing of the timer distributor 4. The outer ends of these sleeves or thimbles 8 and 9 are crimped or bent in-

wardly as indicated at 10 and 11 so as to clamp against the armor 6 at points near the opposite ends thereof and hold the same permanently in place. Without the presence of some means to prevent stretching of the armor coil it will be apparent that upon applying pulling or stretching force thereto it may be stretched and that such force therefore is transmitted to the conductor 2 (which comprises a wire of very small diameter) which is capable of withstanding a relatively small pulling or stretching force. It will be seen, therefore, that any stretching of the armor 6 is very liable to cause breakage or disruption of the conductor 2.

The means employed by me for preventing stretching of the coil consists of a flexible wire 12 located within the armor coil 6 and having its opposite ends bent around and overlying a number of the coils at the oppo-

site ends of the said armor coil, as indicated at 13 and 14. The portions 13 and 14, which are located upon the outside of the adjoining spirals of the coil, are positioned between the thimbles or sleeves 8 and 9 and adjoining end portions of the coil. These end portions 13 and 14 are clamped by the thimbles or sleeves 8 and 9 and held tightly against the adjoining opposite end portions of the armor coil 6. The wire 12 being of substantially the same length as the armor 6 and the opposite ends thereof being anchored within the thimbles or sleeves 8 and 9 it is obvious that a pull upon the armor does not result in the stretching thereof unless the wire 12 should yield. The wire 12 should be of small gage, say one-thirty-second of an inch in diameter, but at the same time it must be strong. For example, a piano wire may be employed and it has been found that such a wire will withstand a pulling tension of upwards of two hundred pounds.

My invention is of especial utility when employed in connection with conductors provided with flexible armors as shown in United States Letters Patent No. 1,631,267, dated June 7, 1927. It will be understood, however, as has been indicated already, that the invention is not limited to flexible armors for the protection of conductors between a switch casing and a timer distributor as illustrated, but may be employed in connection with a flexible armor of the character illustrated wherever the same may be employed for the protection of an electric conductor which is liable to become broken upon the application of a pulling or stretching force thereto.

The invention is of further value and utility than heretofore has been indicated in that by its prevention of the stretching of the coil constituting the armor 6 access to the conductor is prevented whereby the deliberate severing of the latter cannot be effected.

Having thus described my invention, what I claim and desire to secure by Letters Patent is:

1. The combination of an electric conductor, a flexible armor for protecting said conductor, flexible non-stretchable means associated with the said armor and conductor, and means for inclosing and permanently anchoring the opposite ends of the said flexible non-stretchable means.
2. The combination of an electric conductor, a flexible armor of coiled wire inclosing said conductor for protecting the same, the said armor surrounding the said conductor, a flexible non-stretchable means located within the said armor, and means for inclosing and holding the adjoining ends of the said non-stretchable means and the said armor permanently connected with each other and for permanently anchoring the said armor and the said non-stretchable means at their opposite ends.

3. In means for preventing the stretching of flexible armor for electric conductors, the combination of a coil of wire extending around a conductor and constituting a flexible armor therefor, means for permanently anchoring and holding the opposite ends of the said armor and a wire located inside of the said flexible armor, the opposite ends of said wire being bent outwardly and extended in reverse direction outside of the adjoining end portions of the said armor and being clamped between the latter and the said means.

4. In means for preventing the stretching of a flexible armor for electric conductors, the combination of an electric conductor, a flexible stretchable armor surrounding the said conductor to protect the same, thimbles into which the opposite ends of the said armor project and to which they are secured, the opposite ends of the said conductor also extending into the said thimbles, and a flexible wire located within the said armor, the opposite ends of said wire being bent outwardly and extended in reverse direction outside of the adjoining end portions of the said armor and being clamped between the said adjoining end portions and the said thimbles.

5. In means for preventing the stretching of a flexible armor for electric conductors, the combination of an electric current conducting wire, a coiled wire extending around the said conducting wire and constituting an armor therefor, the said armor being stretchable, members having openings into which the opposite ends of the said conducting wire and the said armor extend, a flexible non-stretchable wire located within the said armor and having its opposite ends interlocked with the opposite ends of the said armor, and means whereby the opposite ends of the said armor and the said non-stretchable wire are held permanently within the said openings and in interlocked relation with each other.

In testimony that I claim the foregoing as my invention, I have hereunto signed my name this 2nd day of April, 1928.
